Florian S. Miller
Atty.

UNITED STATES PATENT OFFICE

2,656,820

POWER-OPERATED VISE

Philip S. Becker, Fairview Township,
Erie County, Pa.

Application March 16, 1948, Serial No. 15,079

1 Claim. (Cl. 121—38)

1

This invention relates generally to vises and more particularly to pneumatically operated power vises.

Power vises heretofore provided have had great difficulty in sealing the connections between the sliding pistons therein and their engaging surfaces. This has been particularly troublesome because of the heavy vibration of the vise due to the impact of the jaws. This prior sealing trouble has also made lubrication of the sliding parts of the device very difficult and the wear on the moving parts of these prior power vises has been excessive and considerable replacement of the sliding parts have been necessary.

It is, accordingly, an object of my invention to provide a novel power operated vise which overcomes the above and other defects in presently operated power vises and it is more particularly an object of my invention to provide a power vise which is simple in construction, economical in cost, economical in manufacture, and efficient in operation.

Another object of my invention is to provide novel sealing means for the moving parts of a pneumatically operated power vise.

Another object of my invention is to provide novel sealing means for a pneumatically operated power vise which permits efficient and adequate lubrication of all parts of the moving parts of the vise.

Other objects of my invention will become evident from the following detailed description, taken in conjunction with the accompanying drawings, in which

Figure 1 shows a transverse vertical sectional view of my novel pneumatically operated power vise; and

Figure 2 shows an enlarged partial view taken in section similar to Figure 1 of certain of the parts of my invention.

My invention herein shown may be utilized with any conventional hand operated vise now on the market. The vise itself may be of any suitable form, size and construction. Referring now to the figure in the drawings, I show a fixed jaw 1, a movable jaw 2 having a slide 3 extending through a guide 4 in the fixed jaw 1, and a screw 5 conventionally held from endwise movement having a handle 6 at its front end. In conventional hand vises, the screws have a threaded connection with a stationary nut. The fixed jaw 1 is mounted on or includes a suitable base 7 which in turn is mounted on a work bench. A body 9 is mounted in the rear of the fixed jaw 1 and a piston 10 is connected to the operating

2

screw 5 by the threaded member 14. The body 9 may be mounted on or fixed to the fixed jaw 1. It may be secured to the fixed jaw in any suitable manner. The piston 10 moves in a cylinder 13 at the rear end of the body 9, the cylinder 13 and the piston 10 being axially aligned with the screw 5 and the connecting threaded sleeve nut 14. The piston 10 has a central aperture 15 for receiving the reduced portion 16 of a connecting member 17 having an internal threaded portion 18 for threadable engagement with the threaded end 19 of the sleeve nut 14. A washer 20 and a nut 21 secure the piston 10 on the reduced portion 16 of the connecting member 17. The cylinder 13 has a cap member 22 secured thereto by screw bolts 23. The cap member 22 has a centrally disposed threaded aperture 24 for receiving a screw bolt 25 having a stop nut 26 for limiting the longitudinal movement of the piston 10. The end of the cylinder 13 on one side of the piston 10 is connected to a suitable source of motive fluid, preferably air, through a pipe 27 so so that the piston 10 is thus actuated in one direction only by the motive fluid and in the opposite direction by a spring 28 disposed between the piston 10 and the end cap 22. The end cap 22 has an internally bossed portion 29 for nesting one end of the coil spring 28.

Of particular importance in my novel power vise is the sealing connection between the front wall 50 of the cylinder 13 and the connecting member 17 reciprocable therein. The bore 30 in the wall 50 has a counterbore 32 and a grooved portion 33, spaced from the outer side of the connecting member 17 to permit the insertion of a U-shaped washer or packing ring 35 in the groove 33. The U-shaped packing ring 35 has the forward end 36 thereof adjacent the member 17 formed in arcuate shape so that a small portion thereof does not sealingly engage the outer surface of the connecting member 17 thereby permitting a lubricant to pass thereunder. It will thus be evident that lubricating material may pass both ways along the connecting member 17 past the U-shaped packing ring 35 without destroying the seal between the U-shaped packing ring 35 and the member 17. The piston 10 has an annular washer 40 disposed in an L-shaped peripheral groove 41 and secured by an annular clamping ring 42 and screw bolts 43 to provide a seal between the piston 10 and the inner peripheral surface of the cylinder 13. The lubricating material is supplied to the connecting member 17 through holes 17b and 17d by means of a conventional oil can or the like. The

screws 17a and 17c are provided to close the holes 17b after oil has been applied therethrough. The oil from the holes 17b and 17d falls through the space from the edge of castings 9 and 13 onto the surface of the connecting member 17. Because the packing ring 35 does not sufficiently disturb the oil film on the connecting member 17, it has been discovered that an infrequent oiling of the connecting member 17 in the manner aforesaid is adequate.

In operation, when the air is released from the pressure side of the piston 10 by the opening of the control valve (not shown) in the pipe 27 to exhaust position, the piston 10 is at the right end of the cylinder 13, it being shifted to this position by the spring 28. The vise may then be used as an ordinary hand vise by operation of the handle 6, at which time the sleeve nut 14 will be held stationary against axial and rotary movements. To limit the closing movement, when the vise is operated by power, the screw bolt 25 is withdrawn a distance equal to the amount it is desired to set the closing movement of the jaw 2. For example, if this is one half of an inch, the screw bolt 25 is withdrawn one half of an inch, so that its inner end is spaced one half of an inch from the end of the member 17. When air is allowed to enter the right end of the cylinder 13 through the pipe 27 by the opening of the intake and the closing of the exhaust of the control valve (not shown) the piston 10 is actuated to close the jaws 1 and 2 until the screw bolt 25 is encountered by the end of the member 17. When the control valve is again opened to exhaust, the air from the cylinders 13 passes through the pipe 27 and spring 28 moves the piston 10 to the right end of the cylinder 13, thus shifting the member 17 and connecting sleeve nut 14 and screw 5 as a unit to the right, opening the jaws 1 and 2.

The member 17 is lubricated by any suitable means and because of the arcuate shape of the inner side of the U-shaped packing ring 35 in engagement with the member 17 lubricant will pass from the cylinder 13 to the cylindrical member 9 and vice versa without losing the seal between the U-shaped packing ring 35 and the member 17. Furthermore, upon increases in pressure of the fluid in the cylinder 13, the U-shaped washer 35 will expand thereby always providing a perfect seal between the member 17 and walls 50. It has been found that a slight projecting peripheral portion such as portion 34 adjacent one leg of U-shaped packing ring 35

will hold it in position and against longitudinal movement while still permitting free lateral movement of the leg engaging the member 17.

It will be evident from the foregoing description that I have provided a novel power vise with novel sealing means whereby parts in sliding and frictional engagement are fully lubricated at all times.

Various changes may be made in the specific embodiment of my invention without departing from the spirit thereof or from the scope of the appended claim.

What I claim is:

Fluid operated means for power operating the movable jaw of a vise comprising an open cylinder having a wall with an axial bore and counterbore, a piston slidable in said cylinder, a connecting member between said piston and said movable jaw of said vise slidable axially with said piston and extending through the bore in said cylinder, fluid means for urging said piston for moving said movable jaw, and a U-shaped ring disposed in said counterbore in the wall of said cylinder, said U-shaped ring having the free ends thereof extending toward the inner side of said cylinder and also having the end portions of the inner leg of said U-shaped ring in engagement with said connecting member flared outwardly away from said connecting member whereby a lubricant may pass under said ring in either direction while said ring maintains a seal.

PHILIP S. BECKER.
